Harry Bowen
ATTORNEY

UNITED STATES PATENT OFFICE.

JOHN C. SHERRY, OF WILMINGTON, CALIFORNIA.

LOCK

Application filed June 2, 1925. Serial No. 34,321.

The invention is a lock in which the key is first partially inserted, then turned slightly, then moved further into the lock and turned slightly again and then moved further into 5 the lock again and turned to move the lock bolt.

The object of the invention is to provide a lock that is absolutely impossible to pick.

Another object of the invention is to provide 10 a lock in which the key has a plurality of movements.

A further object of the invention is to provide a lock having a plurality of stages through which the key must pass.

15 A still further object of the invention is to provide a lock having a plurality of stages and dogs for obstructing the direct passage of the key.

And a still further object of the invention 20 is to provide a lock having a plurality of stages in which the key may be placed into the lock from either side.

With these ends in view the invention embodies a lock having a plurality of partitions, each partition having an opening through which the key must pass and engaging dogs adjacent said opening, and a locking bolt that may be operated by the said key after it has passed through the partition. 30

Other features and advantages of the invention will appear from the following description, taken in connection with the drawings, wherein:—

35 Figure 1 is a side view of the lock.

Figure 2 is a cross section through the lock.

Figure 3 is a longitudinal section through the center of the lock showing the locking bolt. 40

Figure 4 is a section similar to that shown in Figure 2 showing a lock of an alternate design.

Figure 5 is a longitudinal section on line 45 5—5 of Figure 4.

Figure 6 is a sectional plan showing the locking member of the lock shown in Figure 4.

Figure 7 is a view showing the arrangement of the locking dogs in the first stage of the lock. 50

Figure 8 is a similar view that may be taken on lines 8—8 of Figures 2 and 4 which shows the position of the locking dogs in the second stage of the lock shown in Figure 4 55

and also the first stage of the lock shown in Figure 2.

In the drawings I have shown my lock as it would be constructed wherein numeral 1 indicates the casing, numeral 2 the lock bolt 60 and numeral 3 the key.

The casing 1 may be of any suitable design and arranged in any suitable manner so that it will be adaptable for any use desired. In the design shown, the casing is provided 65 with three compartments, 4, 5 and 6 with the bolt 2 in the center compartment.

The bolt 2 may also be of any suitable design and arranged in any suitable manner. In the design shown, it is provided with projections 7 at the sides and open spaces 8 and 9 into which the web of the key may slide to 70 operate the bolt as the key is turned.

The key 3 is provided with a tubular shank 10 having a web 11 at one end which extends slightly beyond the end of the shank as shown in Figures 2 and 4. The shank 10 passes over a pin 12 which is attached to the casing and it will be observed that the pin 12 acts as a guide to the key as it passes 80 into the lock.

The web 11 of the key 3 may be of any suitable shape and openings of similar shapes may be provided in the casing to receive it. In the design shown, the web 85 is corrugated and similar corrugated openings 13 are placed in the opposite walls of the casing as shown in Figure 1. It will be observed that when it is desired to open the lock shown in Figures 1, 2 and 3, which 90 is termed a two-way lock as the key only passes to the second stage or into the second compartment, the key is placed through the opening 13 shown in Figure 1 then turned a quarter of a turn so that it may pass

95 through an opening 14 in a partition 15 between the compartments 4 and 5. As it moves from the position in which it enters the lock to the position at the end of the quarter turn, the outer edge of the web will engage a dog 16, which is held by a spring 17, and pivoted on a pin 18, to the partition 15. The dog 16, is made in Figures 7 and 100 8 with a long section 19, and a shorter section 20 and a semi-circular opening 21, in the section 19 and a similar opening 22 in the section 20. The section 19 is also provided with a recess 23 into which an indentation 24 on the spring 17 will snap as the member 19 is moved under the spring and

105 110

the edge of the member 19 may be slightly beveled at the point 25 to permit its passing under the spring.

- It will be observed that as the key is rotated so that the web will move from the vertical position after having passed through the slot 13, shown in Figure 1, the web will engage the member 19 and move it downward so that indentation 24 will snap into the recess 23 and hold the member 16 in the same manner as hereinbefore described for the member shown in Figure 8, and then the key may pass through the vertical slot in the section 23, so that it will enter the next compartment, where the member 16 will be in the position shown in Figure 8. The key may then be rotated so that the web will pass from the vertical to the horizontal position and thereby move the dog 16 and as hereinbefore described so that the key may pass through the opening in the partition indicated by the numeral 27, and into the 3rd section so that it may be rotated to operate the bolt of the lock.
- 25 It will then be observed that as the key is withdrawn from the lock it will be necessary to move it backwards through the same movements and as it is moved from the horizontal to the vertical position it will move the member 16 shown in Figure 8 back to the position shown, so that it may be drawn through the opening shown in Figure 7, at which time the member 19 will be held by the spring 17, and as it is rotated from the vertical to the horizontal position the web will engage the member 20 of the member 16 and rotate the member 16 back to the position shown. The key may then be withdrawn from the lock.
- 40 It will be understood that changes may be made in the construction without departing from the spirit of the invention. One of which changes may be in the use of any number of stages, another may be in the design or arrangement of the bolt, another may be in the design or arrangement of the locking dogs and still another may be in the design of the key.

The construction will be readily understood from the foregoing description. To

use the device, the lock may be installed in doors, cabinets, vehicles or used as a padlock or used for any other desired purpose. It may also be used as a two-way or three-way lock or may have any desired number of states. The key may also be made of any suitable combination of curves or slots to provide a plurality of combinations.

In use, the key may be inserted in the lock as hereinbefore described to operate the bolt and as it is withdrawn the locking dogs will cover the openings so that it will be absolutely impossible to pick the lock. Another feature that makes the lock impossible to pick is the fact that the web openings in the different partitions are at right angles to each other.

Having thus fully described the invention, what I claim as new and desire to secure by Letters Patent, is:—

1. In a multiple stage lock, a plurality of compartments, partitions between the compartments, angularly disposed key openings in the said partitions, closures for each of the said openings, and locking means for engaging the said closures, said openings being adaptable to receive a flanged key which will operate the said closure locks as it passes therethrough.
2. In a multiple stage lock, a casing, a plurality of compartments with partitions between them in the said casing, a pin extending through the said partitions, key openings around the said pin in the said partitions, other openings for the key web in the said partitions, said web openings consecutively arranged at predetermined angles from an entrance opening, closures on the said partitions, and locking means adjacent the said closures.
3. In a multiple stage lock, a casing, a plurality of compartments in the said casing, a pin extending through the said compartments, said compartments having consecutively arranged key openings between them, closures for the said openings, and locking members for the said closures that may readily be operated by a key as it passes through the lock.

JOHN C. SHERRY.
